UNITED STATES PATENT OFFICE

CLYDE GARDNER, DECEASED, LATE OF EBENSBURG, PENNSYLVANIA, BY EDNA B. GARDNER, ADMINISTRATRIX, OF EBENSBURG, PENNSYLVANIA, ASSIGNEE, BY MESNE ASSIGNMENTS, TO GARDNER COMPANY, OF EBENSBURG, PENNSYLVANIA, A CORPORATION OF DELAWARE

CALCULATING MACHINE

Original application filed June 7, 1924, Serial No. 718,678. Divided and this application filed November 5, 1928. Serial No. 317,431.

This application is a division of the application of Clyde Gardner, Serial Number 718,678, filed June 7, 1924. The subject matter described and claimed herein relates to improvement in machines of the class stated.

The principal object of the invention is to improve the type alignment and secure visible printing. This is obtained by forcing the type bars toward the platen into a fixed V shaped aligning bar and when the hammers have fired, to allow the type bar to be restored forward to a position to give the most visibility and at the same time to drop the printing ribbon below the printing line.

These two operations allow the item that has been printed to be seen by an operator without the platen being moved, which is a very desirable feature. No springs are connected to the type, thus allowing a lighter spring to be employed on the hammers. This, moreover produces a clearer print. Spring arms are employed which when the hammers are restored, contact the hammers. The travel of the spring arms is limited so that the hammers need not follow the type against the platen although the hammers are free to follow through the blow that the spring arms give to them and then rebound out of the way of the type, due to the spring arms not forcing the hammers all the way, the hammers being restored by the usual restoring bail.

The foregoing and other objects and advantages will appear as the description proceeds in connection with the accompanying drawings, in which the same reference numerals are used to designate the various parts in all the views, and in which:

Fig. 1 illustrates a right side elevation of the machine partly in section (taken on the line 1—1, Fig. 9) with the parts in normal position.

Fig. 1A is a plan view of the type bars, and the means used for aligning the same.

Fig. 2 is a left hand side elevation, partly in section, taken just inside the left hand side frame, and showing the position assumed by some of the parts illustrated when the "non-print" and the "4" key have been depressed, and with the operating mechanism in its forward position. This view also illus-

trates the counter control keys, "upper", "lower" and "both", with the "lower" counter control key depressed.

Fig. 3 is a right side elevation, partly in section, taken on a line just inside the right hand side frame, the mechanism that has to do particularly with the control and operation of the accumulating section, the parts being shown in their normal position.

Fig. 4 is a plan view of the machine. 60

Reference characters

The reference characters used in this specification are the same as those used to designate the same parts in the specification of the 65 parent application, above referred to.

Totalizer operating mechanism

The counter or accumulator operating mechanism comprises pivoted three-armed 70 actuators 610, Fig. 1, mounted on a shaft 608. One arm 610^a of each lever extends upwardly and is pivoted to an index blade 615 differentially stepped relatively to the numeral keys; another arm 610^b is pivoted to a type 75 bar 611, and the third arm 610^c terminates in a rack which engages the totalizer pinions directly.

The index blades 615 (Fig. 1) are pivotally supported at the rear on studs 654 fixed, one 80 in the upper arm 610^a, Fig. 1, of each of the three-armed levers. These index blades 615 are normally held in rearward position by latches 617 (Fig. 1), which engage studs 659, one on the arm 610^c of each of the levers 610 85 as will be described more in detail hereafter. Springs 683, one for each blade, having one end fastened to the stud 654 and the other secured to the shaft 606, mounted in the plates 614 of an auxiliary frame, tend to 90 draw the index blades forward.

Each index blade 615 is provided with a series of stops 615^b which cooperate with the keys 215 (Fig. 2) so as to allow the index blades 615 to advance distance proportional 95 to the value of the keys 215 depressed. If no key in any order is depressed, the index blade will move forward until stopped by latches 214, one for each order, the rear ends 214^a of which engage with the stop 615^b 100

(Fig. 1), thus setting the type bars 611 for these orders at zero.

Mounted between the side frames 310 Figs. 2 and 3, is a rock shaft 302. Just inside the right frame 310, Fig. 3, and rigidly fixed to this shaft is a three-armed lever 327. One of the arms 327^a is used to release the keys; another 327^b carries a stud 3524 to which is pivoted at one end a link 321, the other end of which is pivoted on a stud 354 in the arm 316, secured to the shaft 301. When the machine is operated by the handle 311, it will through these connections rock the shaft 302. The lever 327 also has another arm 327^c, Fig. 3, which is pivotally connected by a stud 353 to a dash pot 370 of familiar construction. This dash pot is pivotally mounted at 308 to the right side frame 310, Fig. 3.

20 It will thus be seen that the rocking of the shaft 301 will rock the arm 316, and this, in turn, through link 321, will oscillate the lever 327; and since the arm 327^c is connected to the piston of the dash pot by means of 25 the rod 303, the dash pot will regulate the speed of movement of the operating parts upon the return movement of the handle.

25 *Hammer section.*—The hammer section of the printing mechanism is mounted in a special frame in the rear of the machine. This frame consists, primarily, of the side plates 710, 710, Figs. 1 and 1A. These plates have their front ends slotted and supported in grooves in the shaft 306, Fig. 1, while 35 their rear ends are secured on shaft 304. A shaft 706, Fig. 1, extends through the right hand plate 614, then through both plates 710, and has its other end secured in the left hand plate 614 of the supplemental frame. 40 This ties the hammer section to the other parts of the machine.

45 *Type bars.*—As before explained, the type bars 611 are secured one to the rear end 610^b of each of the rack members 610. The ends 610^b of some of these arms are offset to a degree sufficient to bring the type bars 611 together at the rear of the machine. On the side of the upper end of each type bar 611, Fig. 1, is a type cover plate 612, held 50 in place by pins 6531 or any other suitable means. The upper ends of the type bars are slotted to receive the type 6770. The type lie loosely in the type bars, no springs being used to keep the same in place. When the 55 index blades 615 move forward, the associated type bars 611 will be raised distances proportional to the movement of the index blades; and when these blades shall have 60 come to rest against the keys 215, type 6770 corresponding to the value of the keys depressed, will have been brought into printing position.

65 *Impression devices.*—The impression is effected by a special arrangement of hammers and associated elements, all mounted in the

special frame just described. The essential parts of this mechanism are the hammers 715, one for each order; spring actuated hammer operating arms 716, one for each order; hammer lock arms 717, one for each hammer; and triggers 718, one for each lock arm. 73

75 *Hammers.*—The hammers 715 have heads of substantial mass, and each is provided with an extension 715^a Fig. 2. The lower ends of the hammers are mounted on the grooved shaft 701 secured in the frame plates 710, and are slotted so as to be easily placed on and removed from the shaft. At the extreme lower end each hammer is provided with two ledges, one 715^a for cooperation with the 80 ledge 717^b on its companion lock arm 717; and another 715^c for cooperation with its companion spring arm 716.

85 *Spring arms.*—The spring arms 716 are slotted at their lower ends so as to be easily mounted upon, and de-mounted from the slotted shaft 703, Fig. 1, which shaft is secured in the frame plates 710. The upper ends of these spring arms cooperate with the ledges 715^c of the hammers 715. Springs 781, one for each arm, have one end secured to its arm and the other end to a bar 713 arranged between the frame plates 710. These springs are normally under tension and draw the ends of the spring arms against the ledges 85 715^c of their cooperating hammers 715; and when the hammers are released, cause the spring arms to give a striking blow to the hammers. 90

95 *Hammer lock arms.*—The hammer lock arms 717 are slotted at their upper ends, so that they may be readily placed upon, and removed from, the slotted shaft 702, which shaft is mounted in the side frames 710. These lock arms are each provided with a ledge 717^b before referred to, cooperating with the ledge 715^a of its companion hammer 715; and with another ledge 717^c, which cooperates with a ledge 718^a on its companion trigger 718. Springs 782, one for each 100 order, have one end secured to the front end of each lock arm, and the other to a hook on its companion trigger 718, so that these springs tend to hold the lock arms in 105 position, and at the same time tend to raise their companion triggers 718. A rod 709 secured in the side frames 710 lies directly above the rear ends of the lock arms, and serves as a stop to limit the movement of the arms in an upward direction; and another rod 7091, also secured in the side plates 710, lies directly beneath the pivots and prevents the displacement of the lock arms, but permits their movement on the shaft 702. 110

115 *Triggers.*—The triggers 718, one for each order, are mounted for rotation on the slotted shaft 704, which shaft is mounted for bodily movement in arms or cams 711. These arms or cams are pivoted on the shaft 7091, secured in the side frames 710, as just ex- 120

plained. These triggers 718 each have a ledge 718^a, before referred to, for cooperation with the hammer lock arm 717; and each has an elongated rearward extension 718^b, which 5 rests beneath a stud 653 of its cooperating type bar 611. These triggers are held against these studs 653, and are caused to follow the same when the type bars are lifted, by the tension of the springs 782, before 10 referred to. The extension 718^b is of such construction or length that the trigger will still remain beneath its stud 653 when the type bars shall have been moved to printing position, as will be later explained. A rod 15 708 arranged in the cams or arms 711 just below the hooked ends of the triggers prevents them from coming off the shaft 704 but permits their rotation thereon.

Trip frame.—The shaft 704, upon which 20 the triggers are mounted, as before explained, is fixed in the trip arms or cams 711, which, with the shaft 708, constitute a frame pivoted on the shaft 7091. This frame is used to operate the triggers and release the hammers 25 715, to effect the printing stroke. Springs, 783, Fig. 1, each having one end secured to the rod 708, and the other to the stop rod 709, tend to draw this trip frame to the rear, so as to hold the triggers in position 30 for their ledges 718^a to engage the ledges 717^c of their cooperating hammer lock arms 717. This movement is limited by studs 750 one in each cam 717, which under the tension 35 of the springs, are drawn against the margins of the recesses in the plates 710.

This trigger frame is operated by studs 3561 secured one on each of the arms 317, Fig. 2, which are mounted on and oscillate with the shaft 302, as will be explained more 40 at length, under the title "bail operation devices", yet to be described.

Hammer restoring bail.—Cooperating with the hammers 715, and serving to restore the same after they have been operated, is a bail 45 comprising the arms 712 and 7120, Figs. 1A and 2, and the connecting bar 707. The arms are mounted on the shaft 701, and carry rolls 750, Fig. 1A, which are acted upon by cams 317 on shaft 302 and forced to home position, 50 Fig. 2. During the early part of the operation this bail moves away from the hammers, so as to be out of the way of the hammers as they make their striking movement; but near the close of the cycle the cams 317 strike the 55 rolls 750, and operate the bail; and the bar 707, coming against the hammers restores them to home and locked position.

Type bar shifting mechanism.—As before stated, the type bars normally stand so as not 60 to interfere with visual inspection of the platen; but when an impression is to be taken, they are moved bodily to a position where the type may strike the platen, and after printing has been effected are again moved 65 away to normal position. The means for

thus shifting the type bars will now be described.

Pivoted on the ends of shaft 701 are two bars 714, Figs. 1A and 2. These bars are secured at their tops to a spacer 770, and 70 at their lower ends to a short shaft or spacer 705. These arms 714 and spacers 770 and 705 together constitute a bail by which the type bars are moved back and forth.

Secured to the spacer 770 and to the top of 75 the right hand bar 714, are arms 719, each bearing a stud 754, Fig. 1A. These studs 754 are arranged one each in a groove 612^a in the several type cover plates 612. These 80 constitute the means for controlling the upper ends of the type bars. The slots 612^a in the cover plates permit the type bars to move up and down for type selection, but nevertheless always keep them under control. The left hand plate 714 does not carry a stud 754, 85 for the last type bar is controlled by the last arm 719 on the spacer 770.

Bail operating devices.—The bail for operating the triggers, the bail for restoring the hammers, and the bail for positioning the 90 type bars are all operated by the cams 317 secured to the shaft 302, Fig. 2.

These cams 317 carry studs 3561, one on 95 each cam, which cooperate with the trip arms or cams 711, Fig. 1, pivoted on shaft 7091, before described, and depress the same. This draws back the triggers 718, and hammer lock arms 717, until the ledges 717^b of the lock arms 717 are drawn away from the ledges 715^a of the hammers, whereupon the arms 716 100 acting under the influence of their springs 781, shift those hammers which have been released with a striking blow to effect the printing. As the hammers fly to strike, their lower ends contact a shaft 709, Fig. 1, but the 105 parts are so adjusted that the blow is given and then the hammers rebound from the shaft.

The rolls 750 of the bars 712 and 7120 of the 110 hammer resetting bail lie in the path of, and normally rest upon, the cams 317. As the cams move down to the position shown in Fig. 2, due to rotation of the shaft 302, the hammer resetting bail will fall to a perpendicular position, thus leaving the ledges 715^a of the hammers free to engage the ledges 717^b of the hammer lock arms 717, so that they can be released by their respective triggers 718. Upon 115 restoration of the cams 317 to home position, their top edges will strike the studs 750 and force this restoring frame to normal position, the upper rod 707 of this bail forcing the hammers 715 to home position.

As the cams 317 move down to the position 120 shown in Fig. 2, studs 3560 thereon cooperate with the cam faces 714^a on the side arms 714 of the type bar bail, thus oscillating the bail upon its pivots and bringing the upper ends 125 of the type bars to exact printing position. As the cams 317 move to home position, a 130

spring 7801, Fig. 2, restores this bail and the type bars to normal position.

Aliner.—As the type bars move toward the rear to be positioned for printing, they are definitely alined. Fixed at the rear of the machine in any suitable manner is a bar 7092, having a V-shaped front edge; and each and all of the type bars are provided with a series of V-shaped notches, Figs. 1 and 2. As the type bars move back and come to final position just before the printing stroke is taken, the notches engage the bar 7092, and all the type are thus brought to definite position.

What is claimed is:

15. 1. In a recording machine, a platen positioned for visual inspection at the printing line, type carriers each provided with a plurality of type co-operating with the platen, means for adjusting the type carriers to align the individual type to be printed, means for moving the previously adjusted carriers from non-printing to printing position, means for taking an impression from the type, and means for moving the type carriers away from printing position so that the printing may be inspected.
20. 2. In a recording machine, a platen positioned for visual inspection at the printing line, type carriers provided with a plurality of type co-operating with the platen, means for adjusting the type carriers to align the individual type to be printed, means for moving the previously adjusted type carriers bodily toward and away from the platen, and means for taking an impression from the previously selected type.
25. 3. In a recording machine, a platen positioned for visual inspection at the printing line, type carriers provided with a plurality of type co-operating with the platen, means for adjusting the type carriers to align the individual type to be printed, means for moving the previously adjusted type carriers toward and away from printing position, an aligner operable to perfect the alignment as the type carriers are moved to printing position, and means for taking an impression from the type.
30. 4. In a recording machine, a platen positioned for visual inspection at the printing line, type carriers provided with a plurality of type co-operating with the platen, means for adjusting the type carriers to select the desired type, a fixed aligner for the type carriers, means for moving the type carriers to printing position and into engagement with the aligner and away from printing position and out of engagement with the aligner, and means for taking an impression while the type carriers are in printing position.
35. 5. In a recording machine, a platen positioned for visual inspection at the printing line, type carriers provided with a plurality of type co-operating with the platen, means for adjusting the type carriers to select the

desired type, a fixed aligner for the type carriers, means for moving the type carriers to printing position and simultaneously into engagement with the fixed aligner and away from printing position and out of engagement with the aligner, and means for taking an impression while the type carriers are in printing position.

6. In a recording machine, the combination of a platen positioned for visual inspection at the printing line, type carriers provided with a plurality of type co-operating with the platen, means for adjusting the type carriers to align the individual type to be printed, a bail for moving the type carriers toward and away from the platen, and means for taking an impression while the type carriers are adjacent the platen.

7. In a recording machine, a platen positioned for visual inspection at the printing line, type carriers provided with a plurality of type co-operating with the platen, a bail having means for supporting, holding and guiding the type carriers, means for adjusting the type carriers in the bail to align the individual type to be printed, means for operating the bail to move the type carriers toward and away from printing position, and means for taking an impression from the type while they are in printing position.

8. In a recording machine, a platen positioned for visual inspection at the printing line, type carriers provided with a plurality of type co-operating with the platen, a bail having means for supporting and guiding the type carriers in the bail to select the desired type, camming means for positively operating the bail to move the type carriers toward the platen, means for taking an impression from the type while they are in printing position, and means for returning the type carriers to normal position.

9. In a recording machine, a platen positioned for visual inspection at the printing line, type bars provided with aligning serrations, an aligning bar co-operating with the serrations in the type bars, a bail having means for supporting and guiding the type bars, means for positively operating the bail to move the type bars toward the platen and simultaneously to engage the serrations thereof with the aligning bar, and means for restoring the type bars to normal position.

10. In a recording machine, a platen positioned for visual inspection at the printing line, type carriers each provided with a plurality of type co-operating with the platen, means for adjusting the type carriers to select the desired type, hammers for striking the selected type, means for moving the previously adjusted type carriers to printing position between the platen and the hammers, means for giving the hammers a striking blow to

effect the impression, and means for restoring the parts to normal position.

11. In a recording machine, a platen positioned for visual inspection at the printing line, type carriers each provided with a plurality of type co-operating with the platen, hammers for the type, means for adjusting the type carriers to select the desired type, means for moving the type carriers to printing position between the platen and the hammers, means for giving the hammers a striking blow, triggers one for each hammer, means controlled by the type carriers for coupling the triggers with the hammer striking mechanism as the former are adjusted to select the type, means for releasing the hammers of the type carriers which have been adjusted to select the type, and means for restoring the parts to normal position.
12. In a recording machine, a platen positioned for visual inspection at the printing line, type carriers each provided with a plurality of type co-operating with the platen, hammers for the type, means for moving the type carriers to printing position between the platen and the hammers, means for giving the hammers a striking blow, triggers one for each hammer controlled by the type carriers so that only the triggers for the hammers of the type carriers which are adjusted are coupled to their hammer mechanism, means whereby the type carriers which are not adjusted retain control over their triggers while the type carriers are moved to printing position, means controlled by the triggers for releasing the hammers of the type carriers which have been adjusted, and means for restoring the parts.

In testimony whereof, I have hereto affixed
40 my signature.

EDNA B. GARDNER,
Administratrix of the Estate of Clyde Gardner, Deceased.
